UNITED STATES PATENT OFFICE.

WILLIAM W. DEAN, OF CHICAGO, ILLINOIS, ASSIGNOR TO KELLOGG SWITCH-BOARD AND SUPPLY COMPANY, OF CHICAGO, ILLINOIS, A CORPORATION OF ILLINOIS.

CONNECTION TERMINAL AND PLUG.

SPECIFICATION forming part of Letters Patent No. 747,911, dated December 22, 1903.

Application filed December 28, 1900. Renewed May 23, 1903. Serial No. 158,546. (No model.)

To all whom it may concern:

Be it known that I, WILLIAM W. DEAN, a citizen of the United States, residing at Chicago, in the county of Cook and State of Illinois, have invented a certain new and useful Improvement in Connection Terminals and Plugs, of which the following is a full, clear, concise, and exact description, reference being had to the accompanying drawings, forming a part of this specification.

My invention relates to a connection terminal and plug more particularly designed for telephone-switchboards. My object is to provide improved forms of terminal and plug which will enable the construction of a more compact switchboard than has been possible heretofore, and, moreover, to provide structures such that the wear will take place on the plug rather than on the parts of the terminal or socket.

In telephone-switchboards as commonly constructed heretofore, the connecting-plug has been provided with a sleeve adapted to engage a thimble or shell provided in the connection terminal or socket and also with a tip or head, usually spherical in form, adapted to engage a line-spring, the end of the line-spring being built so that the same may be flexed upon the insertion of the plug, the end of the line-spring carrying a ridge or shoulder adapted to engage the rear of the tip or head to thereby firmly and securely hold the plug in position in the socket. Since the plug is cylindrical in form, the plug will occupy different rotated positions upon successive insertions in the socket, and accordingly a different portion of the head or tip will at different times engage the line-spring. The line-spring, however, will be engaged each time at the same locality, and thus while the tip has an infinite number of wearing-surfaces—to wit, the entire periphery of the tip—the line-spring will wear along a single line, and in time this wearing will progress to such a degree as to necessitate the removal of the line-spring and the insertion of a new line-spring in position.

It is the object of the present invention to construct the contacts of the socket and the contacts of the plug so that the wear will take

place on the contacts of the plug rather than on the contacts of the socket. Since there are usually ten times the number of switch-sockets on a switchboard that there are connecting-plugs, the total wear will thus be 55 greatly diminished. Moreover, it is much easier to renew the plug-contacts than it is to renew the contacts of the sockets, since the plugs are exposed and may be readily handled for the purpose of repair, while the 60 socket-contacts are placed in the interior of the board and are usually difficult of access.

A further object of my invention is to render the socket-contacts more compact. The size of the opening of the switch-socket is 65 usually determined by the space necessary for the mounting of the socket-contacts. The plug may usually be made of any size to accommodate the construction of the socket. I propose to do away with the usual laterally- 70 moving contact-spring as heretofore employed in the switch-socket and propose to employ a shell or thimble. Accordingly since there are no laterally-moving parts in the socket the size of the socket may be materi- 75 ally decreased.

Heretofore it has been possible to mount the switch-sockets upon a switchboard so that a maximum of six thousand sockets are within the reach of one operator. In accordance with my invention I am enabled to mount twenty-five thousand sockets within the reach of a single operator. By my invention I am therefore enabled to do away with a great many trunk-lines heretofore 80 employed in large exchanges, and the speed of making connections may thus be materially increased, since one operator may make the connections direct which it has been heretofore necessary to make through the agency 85 of trunk-lines, and consequently with the assistance of one or more operators.

In accordance with my invention in the preferred form I provide the switch-socket with the usual thimble at the forward end of 95 the socket adapted to make contact with the sleeve of the plug, and I employ in addition a second thimble or shell having a suitable shoulder with which a resilient tip on the plug is adapted to engage. I preferably form 100

the shoulder on the thimble so that the same will extend entirely around the thimble and so that the same will be concentric therewith. With this form of thimble I employ a plug 5 having a resilient tip which is eccentrically mounted, so that when the plug is inserted in the socket the resilient tip will ride over the shoulder and will engage the same, whereby the plug will be firmly and securely held 10 in position. I may form the shoulder in the socket eccentric and mount the resilient tip on the plug concentric; but this latter construction, while permitting the formation of a compact socket, transfers the wearing-surface 15 to the socket-contact, and is thus not as advantageous as the first construction above mentioned, in which the concentric shoulder in the socket presents an infinite number of wearing-surfaces, while the tip of the plug 20 presents a single wearing-surface, thus transferring the wear to the plug.

I have illustrated my invention in the accompanying drawings, in which—

Figure 1 is a view showing a number of 25 switch-sockets. Fig. 2 is a view of a portion of the switchboard and a connecting-plug. Fig. 3 is a view showing the switch-socket in section and the plug with the inclosing insulating-sleeve in section. Fig. 4 is a view similar to Fig. 3, showing another view of the plug. Figs. 5 and 6 are detail views of the fastening device employed in the plug. Fig. 7 is a detached view of the plug-tip and associated parts. Fig. 8 is a sectional view showing the plug inserted in the switch-socket. Fig. 9 is a sectional view of a modified form of switch-socket and plug. Fig. 10 is an end view of the socket shown in Fig. 9.

Like letters refer to like parts in the several figures.

The switchboard is preferably built in sections, each section comprising a pair of blocks a a' of rubber or other similar insulating material, the blocks having bores at 45 intervals to receive the contact-thimbles. Each bore in the block a is provided with a thimble b , having a smooth bore and having the ends spun outward, as illustrated, to form a flaring mouth to assist in guiding the 50 plug into position, the flaring ends serving, moreover, to securely maintain the thimble in position. Within the openings in the block a' are mounted the thimbles b' , having the ends similarly spun outward to secure 55 the same in position. The thimble b' carries an inwardly-extending ridge or shoulder b^2 , the shoulder being concentric with the bore of the thimble.

The plug as preferably constructed 60 comprises a metallic cylindrical portion c , the forward end of which is exposed to form the sleeve-contact c' of the plug. One terminal of the cord-connector is adapted to be connected with the part c at the rear end of the 65 plug. Surrounding the part c is a shell c^2 , of rubber or similar insulating material, held in position by means of a threaded collar c^3 , en-

gaging threads carried upon the periphery of the part c . Within the bore of the part c is an insulating tube or sleeve c^4 , and within 70 this sleeve is mounted a bar c^5 of metal, carrying upon the end the rod c^6 , upon the end of which is mounted the tip c^7 of the plug. The tip of the plug is provided with a threaded hole with which the threaded end of the rod 75 c^6 is adapted to engage. The rod c^6 is laterally bent to cause the tip c^7 to occupy an eccentric position relatively to the sleeve c' of the plug. The part c^5 is secured in position by means of a plate c^8 , resting upon an insulating-block c^9 , the screws c^{10} c^{10} being passed through the plate c^8 and block c^9 and engaging tapped holes provided in the part c^5 . The tip-strand c^{11} is connected with the plate 80 c^8 and is thus in electrical connection with 85 the tip of the plug.

When the connecting-plug is inserted in the switch-socket or connection-terminal, the plug-sleeve c' engages the thimble b of the switch-socket, and the tip c^7 of the plug rides 90 over the shoulder b^2 to the position shown in Fig. 8. The tip thus makes electrical contact with the thimble b' , and the engagement of the tip with the shoulder b^2 serves to securely maintain the plug in position. As the 95 plug upon successive insertions in the socket will occupy different positions, the tip of the plug will successively engage the shoulder b^2 at different positions, and therefore while the wear will come upon the tip at a particular 100 point the shoulder will present an infinite number of lines of contact, and the wear upon the shoulder will thus be comparatively slight. Since the tip of the plug is detachable, a new tip may be readily placed in position at any time, and, moreover, the tip 105 may be rotated from time to time relatively to the rod c^6 to thereby present a new contact-surface.

In Figs. 9 and 10 I have illustrated a modification in which the thimble b^3 , adapted to be engaged by the tip of the plug, is provided with an eccentric shoulder b^4 , said shoulder extending around only a portion of the thimble. The tip c^{12} of the plug is held in a concentric position, and when the plug is inserted in the socket the resilient tip is moved laterally as the same passes over the shoulder b^4 and engages the shoulder, as shown in Fig. 9. This construction permits the formation of a socket with as small dimensions as the one above described, wherein the shoulder is concentric; but it has the objection of transferring the wearing-surfaces to the socket. For this reason I prefer in practice 115 to employ the concentric shoulder on the socket and the eccentric tip on the plug.

Having described my invention, what I claim as new, and desire to secure by Letters Patent, is—

1. The combination with a plug having a resilient tip, of a socket to receive the plug and having a shoulder adapted to be engaged by said resilient tip, the engagement of said

- tip and shoulder being eccentric to the center line of the socket and plug, substantially as described. 60
2. A connecting-plug having one terminal in the form of a sleeve and the other terminal in the form of a resilient tip mounted eccentric to said sleeve, substantially as described. 5
3. A connecting-plug having one terminal in the form of a cylindrical sleeve and the other terminal in the form of a resilient tip mounted eccentric to said sleeve, substantially as described. 10
4. A connecting-plug having a portion adapted to enter a suitable socket and provided with a bore in the end thereof, of a resilient rod mounted within said bore and a tip mounted upon the end of said rod and normally maintained in an eccentric position, substantially as described. 15
5. A connecting-plug having a cylindrical portion adapted to enter a suitable socket and provided with a bore in the end thereof, of a resilient rod mounted within said bore and a tip mounted upon the end of said rod and normally maintained in an eccentric position, substantially as described. 20
6. The combination with a socket having a terminal in the form of a thimble, of a plug adapted to be inserted in said socket and having a resilient tip eccentrically mounted to engage said thimble when the plug is so inserted, substantially as described. 25
7. The combination with a socket having a terminal in the form of a thimble provided with a suitable shoulder, of a plug having a resilient tip adapted to engage said shoulder, substantially as described. 30
8. The combination with a plug having a sleeve portion and a resilient tip, of a socket having a cylindrical bore to receive the sleeve portion of said plug, and having a thimble carrying a shoulder adapted to be engaged by said resilient tip, substantially as described. 35
9. The combination with a plug having a cylindrical portion and a resilient tip, of a socket having a cylindrical bore to receive the cylindrical portion of said plug, and having a thimble carrying a shoulder adapted to be engaged by said resilient tip, substantially as described. 40
10. The combination with a plug having a sleeve portion and a resilient tip, of a socket having a bore to receive the said sleeve portion of said plug, and having also a thimble provided with a shoulder adapted to be engaged by said resilient tip, the engagement of said tip and shoulder being eccentric to 45
- the center line of the socket and plug, substantially as described. 50
11. The combination with a socket having a contact-terminal provided with a concentric shoulder, of a plug having a resilient eccentrically-mounted tip adapted to engage said shoulder, substantially as described. 55
12. The combination with a socket having a terminal in the form of a thimble provided with a concentric shoulder, of a plug having a resilient and eccentrically-mounted tip adapted to engage said shoulder, substantially as described. 60
13. The combination with a socket, having two contact-terminals each in the form of a thimble, one of said thimbles carrying a concentric shoulder, of a plug having a sleeve to engage one of said terminals and having a resilient and eccentrically-mounted tip adapted to engage the shoulder on the other terminal, substantially as described. 65
14. The combination with a socket having a terminal in the form of a thimble provided with an inwardly-extending shoulder or ridge, of a plug having a resilient tip adapted to engage said shoulder or ridge, substantially as described. 70
15. The combination with a socket having a terminal in the form of a thimble carrying an inwardly-extending concentric shoulder or ridge, of a plug having a resilient and eccentrically-mounted tip adapted to engage said shoulder or ridge, substantially as described. 75
16. The combination with a connection-socket having only two terminals, one of said terminals being in the form of a thimble and having a bore, and the other terminal being rigid and having a shoulder, of a connecting-plug having two contacts only, said contacts being adapted to register with the said terminals of the connection-socket, one of said contacts being in the form of a sleeve and adapted to engage said thimble when the plug is inserted in the socket, and the other contact being in the form of a resilient rod having a ball or enlargement at its free end, said ball or enlargement being adapted to engage over said rigid shoulder when the plug is inserted in the socket and thereby lock the plug within the socket, substantially as described. 80
